GOLF PRACTICE DEVICE

Charles R. Miller, 15344 Vaughn, Detroit, Mich.

Filed Mar. 28, 1960, Ser. No. 59,919

Term of patent 14 years

(Cl. D34—5)

Fig. 1 is a perspective view of a golf practice device showing my new design;

Fig. 2 is a side elevational view thereof; and

Fig. 3 is an end elevational view thereof.

I claim:

The ornamental design for a golf practice device, as shown.
